UNITED STATES PATENT OFFICE.

WILLIAM T. ARMSTRONG, OF CANTON, MINNESOTA.

SHAFT ATTACHMENT.

1,110,176.

Specification of Letters Patent.

Patented Sept. 8, 1914.

Application filed November 12, 1912. Serial No. 730,830.

To all whom it may concern:

Be it known that I, WILLIAM T. ARMSTRONG, a citizen of the United States, residing at Canton, in the county of Fillmore 5 and State of Minnesota, have invented new and useful Improvements in Shaft Attachments, of which the following is a specification.

My invention relates broadly, to the class 10 of shaft attachment and more particularly to a device devised to prevent such accidents as often occur in connection with horse-drawn vehicle when the horse breaks the tugs or traces and leaves the vehicle.

It is my object to devise a device which 15 connects the ends of the shafts and in event that the horse breaks the tug he is not allowed to leave the shaft and consequently allow the vehicle to run at will.

My invention broadly consists of a pair 20 of caps, each being disposed upon the forward extremity of one of the shafts of the vehicle, and a connecting member in the form of a strap or an elastic member of 25 any kind, or a yieldable member of any kind whereby if the tugs which hold the horse should accidentally break, he will not be allowed to move the shaft.

By the provision of this attachment, it 30 will be readily comprehended that all danger of the reins being caught about the ends of the shafts is obviated and by the provision of this feature, it will be seen that the efficiency of my invention is greatly 35 added to.

With the above and other objects in view, my invention relates to such details of construction and in the arrangement and combination of the several parts as will be hereinafter fully described and specifically 40 pointed out in the appended claim.

In describing my invention in detail, reference will be had to the accompanying drawings wherein like characters denote like 45 or corresponding parts throughout the several views, and in which:—

Figure 1 is a fragmentary view of the ends of a pair of shafts having my attachment applied thereto. Fig. 2 is a side elevation of one of the caps. Fig. 3 is a detail view of the connection between the connecting member and the cap. Fig. 4 is a modification, and Fig. 5 is a modification.

In the accompanying drawings wherein is 50 illustrated the modified and preferred form of my invention, the numeral 10 designates

the shafts, each being of the ordinary form, but it is to be understood that shafts of other forms may be used if occasion should require.

In the drawings, the body portions of the caps are designated by the numeral 11, these body portions being hollow and provided with internal screw threads whereby they may engage the outer extremities of the 60 shafts and be merely held in engagement therewith. Arms 12 are formed upon the body portions, each being substantially semi-circular in form, however, one is comparatively longer than the other and carries a cap 13 at its upper face so as to provide a smooth enlarged surface upon the outer face of the cap, thereby preventing the injury of any one abutting the same.

The ends of the arms do not meet, whereby 65 sufficient space is left to receive the members 14, having wedge shaped slots 15 provided therein and a laterally extending opening 16 as is clearly shown. After the members 14 are moved into place, it will be 70 readily apparent that the connecting member may be easily adjusted as will be hereinafter set forth.

The connecting member comprises a strap 75 17 having a buckle 18 provided upon one end, while a series of apertures 19 are provided at the other end, the latter end being received through the buckle, the tongue 20 of the same engaging the apertures so that the strap can be made either longer or 80 shorter according to the will of the operator.

It will be readily recognized that the entire device can be easily attached and detached to and from the shaft as occasion 85 requires, however, the strap or connecting member can be removed from the caps without taking the latter from the shaft, this being when the horse is to be hitched to the vehicle or to be removed therefrom.

In Fig. 4 I have shown a modified form 90 of cap wherein the body portion is composed of an exteriorly screw threaded shank 21 which is received in an interiorly screw threaded aperture at the end of the shaft, 95 however, the specific form of shaft has not been shown as the form is no part of the present invention.

In Fig. 5 another form is illustrated 100 which consists of the provision of a screw threaded shank 22 carrying a head portion 105 23 upon the upper extremity thereof, the

latter having an extension 24 formed integral therewith as is clearly shown. Arms 25 extend laterally from the extension and provide means for securely holding the 5 members 14 in place after once being inserted therein, thus obviating the danger of the strap from working loose, while each of the different forms of caps have proven efficient in use, it will be recognized that 10 either form may be used if occasion should require.

It is thought from the foregoing that the advantages and novel features of my device will be fully appreciated.

15 I desire it to be understood that I may make slight changes in the construction and in the arrangement and combination of the several parts, provided, however, such changes fall within the scope of the sub- 20 joined claim.

Having thus fully described my invention, what I claim as new and desire to secure by Letters Patent, is:—

25 Guard hooks for vehicle shaft guards comprising in combination, a hook of ring-

like form attached to the end of each shaft and disposed horizontally when the shafts are in a normal position, each ring-like hook being interrupted to form a normally open entrance throat for at- 30 tachment of the guard and the throat of each hook being disposed laterally outwardly of the longitudinal axis of the shaft to thereby form relatively long and relatively short shanks for each hook, the 35 long shank having a large circular head lying transversely of the axis of its respective shaft and forming a shield, and a guard having flexible end members provided with wedge shaped openings longitudinally disposed with respect to the longitudinal axis of the guard and adapted to be forced over said circular heads and into engagement with the long shanks of each hook, sub- 40 stantially as described.

WILLIAM T. ARMSTRONG.
